UNITED STATES PATENT OFFICE.

MELVIN SOLOMON GROH, OF TORONTO, ONTARIO, CANADA, ASSIGNOR TO JOSEPH MERCANTE, OF NEW YORK, N. Y.

AUTOMATIC CONTROLLING DEVICE FOR REFRIGERATING SYSTEMS.

Application filed May 4, 1922. Serial No. 558,414.

My invention relates to automatic controlling devices for refrigerating systems and the object of the invention is to devise a control which will function automatically to keep the temperature in the refrigerator uniform.

A further object is to devise means for automatically opening the water inlet to the condensing coils simultaneously with the throwing in of the motor switch for driving the cooling fluid pump, and a still further object is to devise means situated in the refrigerator for actuating the controlling means, said means being actuated by the variation of pressure of a liquid gas, due to corresponding variation in temperature.

My invention consists of an automatic controlling device constructed and arranged all as hereinafter more particularly described and illustrated in the accompanying drawing in which:

Fig. 1 represents a plan view of the pump and condensing chamber casing, of the form shown and described in my copending applications Serial Numbers 533,905 and 533,906, showing the controlling means in section applied thereto and also the fluid containing means in the refrigerator, said fluid containing means being shown in vertical section.

Fig. 2 is a sectional view through the line 2—2 Figure 1, and

Fig. 3 is an enlarged sectional view of the controlling diaphragm illustrated in Figure 1.

Fig. 4 is a vertical sectional view of Fig. 1, with some of the elements shown in diaphragmatic form instead of section.

Like characters of reference indicate corresponding parts in the different views.

1 is the pump and condensing chamber casing. 50 is a diagrammatic view of the compressor. 60 is a diagrammatic view of the condensing chamber. 70 is a diagrammatic view of the refrigerating element. 55 is the rotary shaft to operate the compressor 50, which is a rotary pump of any desired form. 51 is an upper pump chamber. Said upper pump chamber 51 and said condensing chamber 60 are separated from each other by partition 56, and are both completely closed by the casing 1. 52 is a gas pipe extending from the vicinity of the top of pump chamber 51, and the lower

end of gas pipe 52 extends into the condensing chamber 60. 58 is a cooling coil, fed with water by boss 25, and discharging said water through outlet 54. 71 is a pipe connecting the evaporator or refrigerating element 70 with compressor 50. 72 is a pipe connecting condensing chamber 60 with evaporator or refrigerating element 70. 90 is a valve in the line of pipe 72 to function in the usual manner between the condensing chamber 60 and the evaporator or refrigerating element 70. 2 is the refrigerator. 3 is a casing opened at one side, applied to the side of the casing 1 and adapted to contain the double diaphragm capsule 4 which is secured to the annular plate 5, which has the passage-way 6 extending therethrough, said plate being capable of being slid inwardly and outwardly in the casing 3. The outer end of the passage-way 6 is connected by means of the pipe 7 to a phial 8, situated in the refrigerator and adapted to contain any suitable liquid such as ammonia or sulphur dioxide, the valve 9 being provided for the purpose of introducing the liquid into the phial before the pipe 7 is applied to such valve, such valve being closed when the phial is filled prior to the connecting up of the pipe 7. The inner end of the passage-way 6 communicates with the interior of the capsule 4.

10 is a stud provided on the outer face of the plate 5 and adapted to extend freely through an orifice 11 in the casing 3.

12 is a lever pivoted intermediately of its length to the bracket 13 on the casing 3 and having its longer end extending across such casing.

14 is a stud extending freely through the extremity of the longer end of the lever 12 and provided with a thumb nut 15 threaded onto its free end. 16 is a spring interposed between the thumb nut and the lever 12 for normally holding the said lever in engagement with the stud 10.

The shorter end of the lever 12 projects past the casing 1 and engages the valve stem or push rod 17 of the valve 18 which is reciprocable in the valve chamber 19, suitably disposed in the casing 20, said valve 18 being normally held closed on its seat by means of the spring 21 which is held in the valve chamber by means of a screw plug 22 which closes the open end thereof.

The valve chamber 19 communicates 110

through the valve seat 23 with a longitudinal passage-way 24 which communicates in turn with the boss 25 connected with the cooling coils in the interior of the pump 5 and condensing chamber casing 1. 26 is a water inlet to the valve chamber 19, said inlet being adapted to be connected to the water main.

27 is a stuffing box or gland through 10 which the valve stem 17 extends, said stuffing box preventing any water getting out from the passage-way 24.

28 is a screw plug valve extending into the passage-way 24 and adapted to partially 15 close the same, said plug valve having a stem 29 extending through a stuffing box 30 in the casing 20, said valve being adapted to be operated by the thumb nut 31 situated exteriorly of such casing. 32 is a cylindrical chamber constituted in the casing 20 and communicating with the passage-way 24 at the opposite end to the boss 25, said cylindrical chamber containing a reciprocable piston 33 normally held at the passage- 25 way end of the cylindrical chamber by the spring 34, said piston being provided with the piston rod 35 extending out of the casing through the stuffing box 36, and its free end pivotally connected by the link 37 with 30 the lever 38 of the switch 39 which is connected in the pump motor circuit.

40 (shown in dotted lines in Figure 2) is a by-pass leading from the portion of the passage-way 24 between the plug valve 35 28 and the boss 25 to the cylindrical chamber 32 in the vicinity of its outer end.

The operation of my controlling device is as follows:

As is well known in the prior art the 40 refrigerating fluid is compressed by compressor 50 and when so compressed is heated and passes into pump chamber 51, and it then passes through gas pipe 52 into condenser 60. In this condensing 45 chamber 60, the refrigerating fluid is cooled and condensed into liquid form by the cold water flowing through cooling coil 53. The refrigerating fluid when so cooled and condensed, being still under pressure 50 from the compression force of compressor 50 through pump chamber 51, gas pipe 52, and condensing chamber 60, is forced into pipe 72, through valve 90 and into refrigerating element 70. In refrigerating element 70, the refrigerating fluid eventually 55 passes into pipe 71, and thence back into compressor 50; from which the above mentioned cycle begins anew.

The particular features of my controlling 60 device are as follows:

It is to be understood that the valve 9 is opened immediately the pipe 7 is connected thereto. When the temperature in the 65 refrigerator 2 rises, the gas in the phial 8 expands and as the pipe is connected through

the passage-way with the interior of the capsule 4, the diaphragm of such capsule will be expanded. The expansion of the inner diaphragm is limited, as it will engage the wall of the pump and the condensing chamber casing 1 and consequently the expansion of the outer diaphragm will cause the plate 5 to be moved outwardly, thus causing the stud 10 to actuate the longer end of the lever 12 in an outward direction. The smaller 75 end of the lever is consequently moved inwardly and as this lever is in engagement with the valve stem 17, such valve stem moves the valve 18 into the open position, permitting the water from the main and the 80 inlet 26 to traverse the valve chamber 19, orifice 23, passage-way 24 hollow boss 25 and circulate the water through the cooling coils in the condensing chamber of the casing 1.

Owing to the restricting of the passage- 85 way 24 by the plug valve 28 it will be seen that the water in the inlet valve portion of the passage-way will have a greater pressure than in the discharge end of the passage-way and consequently as the discharge 90 portion of the passage-way 24 is connected by the by-pass 40 with the outer end of the cylindrical chamber 32, it will be seen that the back pressure of the water in the inlet valve portion of the passage-way 24 will 95 actuate the piston 33 into its outermost position and when this occurs the piston rod 35 will throw the switch lever 38 over, closing the pump motor circuit through the medium of the switch 39. Consequently the 100 pump will be actuated and the cooling fluid, such as sulphur dioxide, circulated through the refrigerating apparatus.

When the temperature in the refrigerator falls to the requisite extent the gas in the 105 phial 8 will contact, releasing the pressure in the capsule 4 and through the medium of the spring 16 restoring the lever 12 to the position illustrated in Figure 1, the spring 21 restoring the valve 18 to its closed position and keeping the valve stem 17 in engagement with the end of the lever 12. When the valve 18 is closed it will be seen that the pressure of the water in the passage-way 24 on both sides of the valve 28 110 will be equalized with the pressure of water at the other side thereof which is communicated to the cylindrical chamber through the by-pass 40. The spring 34 will consequently restore the piston to the initial or 115 inoperative position illustrated in Figure 2 of the drawing, thus throwing over the lever 38 of the switch 39 and breaking the motor circuit. Therefore as the motor circuit is broken, the supply of water to the 120 cooling coils in the condensing chamber will be simultaneously cut off.

From the above description it will be seen that I have devised a simple and effective 125 automatic controlling device for refrigerator 130

systems which will be dependent upon the change of pressure of gas evolved from liquid in the thermostatic element and will actuate simultaneously the means for admitting the water to the cooling coils of the condensing chamber with the closing of the switch in the pump motor circuit. Thus both the water for condensing the cooling fluid and the circulation of the cooling fluid itself will be controlled automatically.

I have further devised a controlling device which will be comparatively cheap in construction and simple in operation and which will be actuated without the addition of any electric or other motive power.

The valve 28 can be adjusted as required so that the flow of water to the condensing coils can be varied to suit different requirements by adjusting the thumb nut 31; and the spring 16 can be so tensioned as to vary the actuation of the lever 12 dependent upon the expansion of the capsule 4 due to rise of temperature in the refrigerator.

It will also be apparent that should the water supply from the main fail, the motor circuit will be automatically broken by the returning of the piston 33 to its initial position.

What I claim as my invention is:

- 30 1. In automatic controlling devices for refrigerating systems; a compressor adapted to compress the refrigerating fluid; a condenser; means adapted to transfer the refrigerating fluid from said compressor into said condenser; a cooling coil within said condenser, said cooling coil being adapted to be fed with cooling water; a passage way for cooling water into said cooling coil; a refrigerating element; means adapted to transfer said refrigerating fluid from said condenser into said refrigerating element; means adapted to transfer said refrigerating fluid from said refrigerating element back to said compressor; a phial containing a fluid readily evaporable, said phial being located in close proximity to said refrigerating element; a diaphragm operable by the entrance of the evaporated fluid from said phial; a lever operable by said diaphragm; a valve operable by said lever, said valve being adapted to open or close said passage way for cooling water into said
- cooling coil; a plug valve in the inlet valve portion of said passage way; a cylindrical chamber; a piston longitudinally operable within said cylindrical chamber, the inner face of said piston being in contact with the inlet valve portion of said passage way; a bypass from the discharge portion of said passage way into the outer end of said cylindrical chamber, whereby when said valve is operable by said lever closes said passage way of water into said cooling coil the back pressure of the water in the inlet valve portion of said passage way exceeds the pressure of the water in the discharge portion of said passage way, and actuates said piston into its outer position; a piston rod connected with said piston; a switch lever actuated by said piston rod; and an electric circuit adapted to be opened or closed by said switch lever, said electric circuit when closed being adapted to operate the said compressor, and said electric circuit when open being adapted to stop the operation of said compressor.
2. In automatic controlling devices for refrigerating systems; a thermostatic element operable by the temperature of the refrigerating element; a passage way for water; a valve operable by said thermostatic element, said valve being adapted to open or close said passage way for water; a plug valve in the inlet valve portion of said passage way; a cylindrical chamber; a piston longitudinally operable within said cylindrical chamber, the inner face of said piston being in contact with the inlet valve portion of said passage way; a bypass from the discharge portion of said passage way into the outer end of said cylindrical chamber, whereby when said valve is operable by said lever closes said passage way of water, the back pressure of the water in the inlet valve portion of said passage way exceeds the pressure of the water in the discharge portion of said passage way and actuates said piston into its outer position; a piston rod connected with said piston; a switch lever actuated by said piston rod; and an electric circuit adapted to be opened or closed by said switch lever.

MELVIN SOLOMON GROH.

systems which will be dependent upon the change of pressure of gas evolved from liquid in the thermostatic element and will actuate simultaneously the means for admitting the water to the cooling coils of the condensing chamber with the closing of the switch in the pump motor circuit. Thus both the water for condensing the cooling fluid and the circulation of the cooling 10 fluid itself will be controlled automatically.

I have further devised a controlling device which will be comparatively cheap in construction and simple in operation and which will be actuated without the addition 15 of any electric or other motive power.

The valve 28 can be adjusted as required so that the flow of water to the condensing coils can be varied to suit different requirements by adjusting the thumb nut 31; and 20 the spring 16 can be so tensioned as to vary the actuation of the lever 12 dependent upon the expansion of the capsule 4 due to rise of temperature in the refrigerator.

It will also be apparent that should the 25 water supply from the main fail, the motor circuit will be automatically broken by the returning of the piston 33 to its initial position.

What I claim as my invention is:

1. In automatic controlling devices for refrigerating systems; a compressor adapted to compress the refrigerating fluid; a condenser; means adapted to transfer the refrigerating fluid from said compressor into 30 said condenser; a cooling coil within said condenser, said cooling coil being adapted to be fed with cooling water; a passage way for cooling water into said cooling coil; a refrigerating element; means adapted to 35 transfer said refrigerating fluid from said condenser into said refrigerating element; means adapted to transfer said refrigerating fluid from said refrigerating element back to said compressor; a phial containing a 40 fluid readily evaporable, said phial being located in close proximity to said refrigerating element; a diaphragm operable by the entrance of the evaporated fluid from 45 said phial; a lever operable by said diaphragm; a valve operable by said lever, said valve being adapted to open or close 50 said passage way for cooling water into said

cooling coil; a plug valve in the inlet valve portion of said passage way; a cylindrical chamber; a piston longitudinally operable within said cylindrical chamber, the inner face of said piston being in contact with the inlet valve portion of said passageway; a bypass from the discharge portion of said passageway into the outer end of said cylindrical chamber, whereby when said valve operable by said lever closes said passageway of water into said cooling coil the back pressure of the water in the inlet valve portion of said passageway exceeds the pressure 60 of the water in the discharge portion of said passageway, and actuates said piston into its outer position; a piston rod connected with said piston; a switch lever actuated by said piston rod; and an electric 65 circuit adapted to be opened or closed by said switch lever, said electric circuit when closed being adapted to operate the said compressor, and said electric circuit when open being adapted to stop the operation of 70 said compressor.

2. In automatic controlling devices for refrigerating systems; a thermostatic element operable by the temperature of the refrigerating element; a passageway for 80 water; a valve operable by said thermostatic element, said valve being adapted to open or close said passageway for water; a plug valve in the inlet valve portion of said passageway; a cylindrical chamber; a piston 85 longitudinally operable within said cylindrical chamber, the inner face of said piston being in contact with the inlet valve portion of said passageway; a bypass from the discharge portion of said passageway into the 90 outer end of said cylindrical chamber, whereby when said valve operable by said lever closes said passageway of water, the back pressure of the water in the inlet valve portion of said passageway exceeds the pressure 95 of the water in the discharge portion of said passageway and actuates said piston into its outer position; a piston rod connected with said piston; a switch lever actuated by said piston rod; and an electric 100 circuit adapted to be opened or closed by said switch lever.
